UNITED STATES PATENT OFFICE.

HARRY JACOB WERTHEIMER, OF CHICAGO, ILLINOIS.

PROTECTIVE INSTALLATION.

Application filed November 16, 1922. Serial No. 601,323.

To all whom it may concern:

Be it known that I, HARRY JACOB WERTHEIMER, a citizen of the United States, and a resident of the city of Chicago, in the county 5 of Cook and State of Illinois, have invented certain new and useful Improvements in a Protective Installation; and I do hereby declare that the following is a full, clear, and exact description of the same, reference being had to the accompanying drawings, and to the numerals of reference marked thereon, which form a part of this specification.

This invention relates to an improved protective installation and particularly to 15 an installation of protective means and apparatus which is designed to protect commercial institutions, dwelling houses, mail cars and the like from the depredations of burglars and other persons not authorized 20 to enter the same.

It is an object of the present invention to provide apparatus preventing the escape of the burglar and designed to trap and confine the burglar in a definite compartment 25 where it will not be possible for other occupants of the building or the like to be injured.

It is another object of this invention to provide an apparatus adapted to be automatically moved into operative position to 30 close all apertures opening into a building or other room, or any room thereof, to prevent the escape of unauthorized persons therefrom and to prevent the spread of fire 35 in the building.

It is also an object of this invention to provide an installation of the kind described including flexible sheet metal protective curtains.

40 It is an important object of this invention to provide a protective installation wherein the protecting means are successively brought into operation to facilitate the confinement of a burglar or other unauthorized person within an isolated compartment.

45 It is finally an important object of this invention to provide an automatic installation of the class described which is adapted to give an alarm when set in operation and which is provided with power operated automatic resetting means.

50 Other and further important objects of the present invention will be apparent from 55 the disclosures in the specification and the accompanying drawings.

The invention (in a preferred form) is shown in the drawings and hereinafter more fully described.

On the drawings:

Figure 1 is a perspective view, with parts 60 broken away, illustrating certain apparatus embodying the installation of this invention.

Figure 2 is a top plan view, with parts 65 in section, illustrating the apparatus embodying the present invention.

Figure 3 is a fragmentary enlarged section along the line 3—3 of Figure 2.

Figure 4 is a fragmentary enlarged section 70 on the line 4—4 of Figure 3.

Figure 5 is a section along the line 5—5 of Figure 2, with parts omitted.

Figure 6 is a section on the line 6—6 75 of Figure 5, with parts omitted and parts in elevation.

Figure 7 is a section on the line 7—7 of Figure 5, with parts omitted and parts in elevation.

Figure 8 is a view taken along the line 8—8 of Figure 7, with parts in elevation and 80 parts in section.

Figure 9 is a view taken along the line 9—9 of Figure 8.

Figure 10 is a vertical detail section illustrating the construction of the protective 85 curtain.

Figure 11 is an enlarged detail illustrating one of the clutch releasing devices and a supporting means therefor.

Figure 12 is a section on the line 12—12 90 of Figure 11, with parts in elevation.

Figure 13 is a perspective view of a vestibule adapted to be equipped with the improved protective installation of this invention.

Figure 14 is a horizontal section through a building equipped with the improved protective installation.

Figure 15 is a view similar to Figure 14 taken through a mail car.

Figure 16 is a wiring diagram illustrating the electrical connections used with the raising motor.

Figure 17 is a wiring diagram illustrating 105 electrical connections used with the lowering motors.

As shown on the drawings:

A mechanism accomplishing the objects of this invention is shown on the drawings and will now be described, it being understood that details of this mechanism may 110

be considerably varied to meet the needs of particular installations.

In Figure 14 the reference numeral 1 represents an enclosure such as a bank, store, dwelling-house or the like, which is provided with a plurality of windows, doors and other openings thereinto, each of which openings is adapted to be closed against entrance or exit by means of a shield or curtain of steel or other impenetrable material which is moved into protective position by mechanism and in a manner to be described hereinafter. The main entrance to the room or building which is protected by this installation is preferably provided with a vestibule such as is indicated by the reference numeral 2 in Figure 14, the entrance to, and the exit from said vestibule being adapted to be closed by protective shields or curtains of the type heretofore mentioned. A diagrammatic illustration of such a vestibule is shown in perspective in Figure 13, and it will be noted that the construction thereof is such that the various operating mechanisms may be effectively concealed beneath the floor and in the side walls of the vestibule. In Figure 15 I have diagrammatically illustrated a mail car which is adapted for the protective installation of this invention, said mail car being designated as a whole by the reference numeral 3 and being provided with side door closures 4 of the usual type. Extending inwardly from one of said closures are lateral walls 5 which afford a vestibule entrance, the end of which is adapted to be closed by a steel protective curtain embodying the principles of the present invention. The closure 4 opposite the vestibule entrance is of course also provided with a similar concealed protecting curtain.

In the installation illustrated herein there are two types of protective shields or curtains, each of which is preferably constructed of relatively narrow strips of steel or other substantially impenetrable, fireproof material, which are hinged together in the manner indicated by the reference numeral 6 in Figure 10. The protective shield or curtain for the outer entrance of the vestibule and the mechanism for operating the same will now be described in detail. Said protective shield which is indicated by the reference numeral 7 is adapted to be rolled on a suitable roller 8 which is rotatably mounted beneath the floor of the building or other enclosure and which is adapted to be driven through a shaft 9 and bevel gears 10 and 11, which in turn are driven from a motor 12 through an automatically operated clutch 13 and suitable reduction gearing 14 and bevel gears 15 and 16, best shown in Figure 2. Secured to the upper edge of the curtain 7 is a reinforcing strip 17, the outer ends of which are formed to slidably

engage guide rods 18 and 19 which are respectively mounted on either side of the door or other opening and are concealed inside the frame thereof. The vertical guide rod or shaft 19 is rotatably mounted and is adapted to be driven through bevel gears 20 and 21, and a shaft 22, from a motor 23, through suitable reduction gearing 24 and bevel gears 25 which are best shown in Figure 2. This drive from the vertical shaft 19 or rod 19 is transmitted through bevel gears 26 and 27 and an automatically operated clutch 28 to a horizontal shaft 29 which is rotatably mounted above the door or other closure and inside the upper frame thereof. Mounted on the horizontal shaft 29 near each end thereof adjacent the shafts or rods 18 and 19 are sprocket wheels 30 and 31 which are respectively engaged by sprocket chains 32 and 33 which are connected at one end to the reinforcing strip 17 on the curtain 7 and which have weights 34 and 35 respectively connected to their free ends, the weight 34 being movable on a guide 36, and the weight 35 being movable on a guide 36a.

The protective shield or curtain installation just described is used in connection with the outer door of the vestibule of the building, railway car or the like, and is the one which is initially set in operation. A slightly different type of protective shield or curtain is used in connection with the remainder of the doors and windows and is also used at the inner end of the vestibule. These protective shields which are controlled automatically by means of mechanism associated with the protective shield or curtain 7 will now be described. Curtains or shields 37 similar to the curtain 7 are provided for each of the window and door frames and said curtains are adapted to be wound or rolled on rollers 38 journaled on a suitable axial shaft 39 beneath the frame of the door or window. The upper end of each of said curtains 37 is provided with a reinforcing strip 40, the outer ends of which are formed to slidably engage guide rods 41 and 42 which are mounted inside of the frame of the door or window and parallel to the vertical portions of said frame. Suitably journaled above the frame of the door or window and in alignment with one edge of the curtain 37 is a pulley 43 and a double pulley 44 is similarly journaled opposite said pulley 43 and in alignment with the other edge of the curtain 37. Secured to one end of the reinforcing strip 40 is a flexible member 45 which may consist of rope, chain, cable or any suitable material and which extends upwardly around the pulley 43 and then transversely to the pulley 44, from said pulley 44 downwardly to connection with a boss 46 on a weight 47 which is slidably mounted on a guide rod 48 parallel to the

guide rod 42 and adjacent thereto. Extending upwardly from the other end of the reinforcing strip 40 is a flexible member 49 similar to the flexible member 45 and said flexible member 49 extends over the double pulley 44 and thence downwardly to and is connected with the boss 46. The weight 47 is made sufficiently heavy so that the action of gravity thereon will cause the same to rapidly descend, thus causing a rapid upward movement of the curtain or protective shield 37 to close the window or door in which said shield is applied. The weight 47 is normally held in raised position by means of a spring latch 50 which is adapted to engage in notches in an extension 51 on the upper end of said weight and which is adapted to be released to release the weight by a link 52 which is operated through a pivoted bell-crank lever 53. When the curtain 37 is moved into operative position by descent of the weight 47, the end of the reinforcing strip 40 which slidably engages the guide rod 41 contacts a forked arm 54 which is pivotally mounted near the upper end of said guide rod and the movement thus imparted by this contact with the forked arm 54 is transmitted to a pivoted lever 55 which acts to close a switch 56 connected in the circuit of an electric motor 57 which is adapted to be manually set in operation to rotate the shaft 39 thereby causing the curtain 37 to be rolled on the roller 38. A connection between the shaft 39 and the motor 57 is afforded by bevel gears 58 and 59, an automatically operated clutch 60, a shaft 61 and reduction gearing which is indicated as a whole by the reference numeral 62. Said automatically operated clutch 60 is adapted to be moved into engagement by means of a suitable fork 63 which is connected to a pivotally mounted weight 64, the release of said weight allowing the same to rotate about its pivot point and causing the jaws of the clutch to be moved into engagement. Said weight 64 is normally held in unreleased or upward position by the engagement of a spring latch 65 with notches formed in the upper end of a vertical extension arm 66 on said weight. The release of said spring latch 65 is effected through a link 67 which is operated by a bell-crank lever 68, one arm of which is pivotally connected to a member 69 which in turn is connected to a link 70 extending to the lever 55. As a result of this arrangement, the weight 64 is released to move the clutch into operative position upon the movement of the curtain 37 into upward or operative position and the consequent contacting of the forked lever 54 by the end of the reinforcing strip 40.

When the curtain 37 is moved to downward or inoperative position by means of the above described operation of the motor

57, the switch 56 is opened and the clutch 60 disengaged. This is effected by the contacting of a pivoted forked lever 71 by the under side of the end of the extension 40. This contacting of said lever 71 acts to rotate the same about its pivot point, forcing the outer end thereof into contact with a horizontal extension 72 on the member 69, and thus imparting a downward pull on the link 70 to open the switch 56. At the same time the inner end of the lever 71 is moved upwardly, and this upward movement is transmitted to a pivotal connection with an extension arm 73 on said weight 64, the weight thus being rotated upwardly about its pivot point into such position that the spring latch 65 can again engage in one of the notches in the extension portion 66. This upward movement of the weight 64 is of course transmitted through the fork 63 to disengage or receive the clutch 60. Substantially simultaneously with the release of the clutch 60, the weight 47 will have been moved into position so that the spring latch 50 is engaged in one of the notches in the extension 51 on the weight 47, thus maintaining said weight in raised position.

A connection effecting the automatic release of the spring latch 50 to allow descent of the weight 47 and movement of the curtain 37 into operative position will now be described. Connected to one end of the bell-crank lever 53 is a link 74 which extends downwardly to a pivoted bell-crank lever 75 and is connected to one arm thereof. Connected to the other arm of said bell-crank lever 75 and extending substantially horizontally is a link 76 which in turn is connected to one arm of a pivoted bell-crank lever 77 which is pivotally mounted adjacent the guide rod 19. Extending upwardly from the other arm of said bell-crank lever 77 is a link 78 which is connected to a pivoted member 79, the outer end of which is adapted to be contacted by the end of the reinforcing strip 17 to be moved upwardly into the dotted line position shown in Figure 1, thus causing a release of the spring latch 50 through the connections just described.

The particular protective shield or curtain 37 and attendant mechanism just described are adapted to be mounted at the inner end of the vestibule, but exactly the same installations are adapted to be mounted in all of the doors and windows of the particular enclosure to which the installation is applied, and the automatic control for these curtains is effected through a pivoted lever 80 similar to the lever 79 and mounted therebelow so that the operation thereof and the movement of the protective shield for the various doors and windows is effected prior to the operation of the protective shield or

curtain 37. A connection from the pivoted lever 80 to the controlling spring latches at the various doors and windows is effected through a link 81 which is connected near the outer end of said lever 80 and which extends downwardly to a connection with one arm of a pivoted bell-crank lever 82, the other arm of which is connected to a link 83 which affords, through suitable connections adapted to the particular installation, a connection with the various spring latches similar to the spring latch 50.

Upward movement of the curtain 7 is effected in the manner previously described through rotation of the shaft 29 and the connection of said shaft for rotation is made through the clutch 28 which is held in engagement during the upward movement of the curtain by means of a pivoted weight 84 which is pivoted at 85 and which is provided with an upwardly extending arm 86 which is connected to a portion of the clutch 28 so that when said weight 84 moves downwardly the clutch 28 is engaged in operative position. When the curtain 7 reaches the upper limit of its travel, the free end of the weight 84 is again moved upwardly to release the clutch 28 by contact of the end of the reinforcing strip 17 with a forked extension 87 on said weight which is engaged on either side of the shaft 19. Said weight 84 is held in upward or clutch releasing position by engagement of a spring latch 88 with one of a series of notches formed in an upward extension 89 on said weight 84. A release of said spring latch 88 is effected during the downward movement of the curtain through a link 90 which is connected to one arm of a pivoted bell-crank lever 91, the other arm of which has connected thereto a link 92 extending downwardly to a pivoted lever 93, the outer end of which is adapted to be contacted by the under side of the end of the reinforcing strip 17, during the downward movement of the curtain. Thus, during the downward movement of the curtain, at the point when the same has been moved downwardly sufficiently to move into concealed position, said lever 93 is contacted to release the spring latch 88, the weight 84 is allowed to move downwardly and again cause operative engagement of the clutch 28, automatically connecting the curtain to be again raised through the operation of the motor 23. This downward movement of the curtain is also transmitted to a pivoted T-lever 94 which is moved into position to allow the opening of a switch 95 in the circuit of the motor 12 and at the same time to cause a closing of a switch 96 in the circuit of the motor 23, thus stopping the motor 12 and ceasing the downward movement of the curtain and at the same time placing the circuit of the motor

23 in such position that the curtain 7 may again be raised.

The operation of the T-lever or plate 94 is effected through a link 97 connected thereto and extending downwardly to a member 98 which has a horizontal extension 99 extending under one end of a pivoted forked lever 100 which is engaged on either side of the shaft 18. It will of course be obvious that the downward movement of the curtain causes the under side of the end of the reinforcing strip 17 to contact the forked end of the lever 100, causing downward movement thereof, said downward movement being transmitted through the link 97 to the T-plate or lever 94. The downward movement of the forked end of the lever 100 of course causes the other end thereof to be moved upwardly, and this upward movement is transmitted to a pivoted weight 101, through a pivotal connection of the outer end of said lever 100, with an upwardly extending member 102 on said member 101. Said weight 101 is pivoted at 103, as the raising of the free end thereof in the manner just described acts to release the clutch 13, a connection between the weight and the clutch being afforded by an ordinary clutch fork 104. When the curtain 7 is rolled down into inoperative position said weight 101 is held upwardly to maintain the clutch 13 in disengaged position by the engagement of a spring latch 105 with one of a series of notches formed in an upwardly extending member 106 on said weight 101. When the curtain is moved upwardly into operative position the end of the T-plate or lever 94 which is connected to the link 97 is contacted by the reinforcing strip 17 and is moved upwardly, thus moving the link 97 upwardly, and this upward movement of the link 97 is transmitted through a bell-crank lever 107 and a link 108 to release the spring latch 105 and thus allow the weight 101 to drop and move the clutch 13 into engaged and operative position. This movement of the T-plate 94 is simultaneously transmitted to close the switch 95 in the circuit of the motor 12, and to allow the opening of the switch 96 in the circuit of the motor 23.

As has been before stated, the operating mechanisms for the protective shield or curtain are entirely concealed beneath the floor and inside the walls adjacent the door and window frames. In Figures 11 and 12, I have illustrated a convenient form of bracket 107^a which is provided with a transverse supporting member 108^a and which may be employed as a support for the shaft 39 and the mechanism for rotating said shaft and controlling the operation thereof.

The means whereby the various mechanisms are enclosed and concealed may be best seen from an examination of Figures

2, 3, 4 and 13, wherein the reference numeral 109 represents the inner wall of the building, room or vestibule, wherein the reference numeral 110 represents the outer walls thereof. The floor is designated by the reference numeral 111 and narrow openings in the floor and in the side walls permit of the free upward and downward movement of the protective shields or curtains. The narrow opening in the floor 111 is preferably normally closed by a hinged strip or spring door 112 which is pushed upwardly into open position by the upward movement of the protective shield or curtain. The narrow openings in the side walls 109 are normally concealed by strips 113 which are guided by the side walls themselves and resiliently held over the narrow openings by light helical springs 114. The lower ends 20 of said strips 113 are beveled in the manner indicated in Figure 3, so that the upward movement of the protective shield or curtain will serve to push the same rearwardly out of the way, compressing the springs 114. Said strips 113 are preferably formed in the manner indicated in Figure 4 so as to slidably engage each side of the wall 109, said wall thereby acting as a guide for said strip. The ceiling of the room or the top of the door frame indicated by the reference numeral 115 is preferably provided with a groove 116 in which the reinforcing strip on the top of the curtain or protective shield is engaged when the same is moved into operative or protecting position.

Figures 16 and 17 diagrammatically illustrate the electrical connections which are used in the installation of this invention. Figure 16 illustrates the electrical connection employed in connection with the motor 23 which is employed for raising the curtain 7. These connections include a main control or line switch 117 which is preferably locked in a control box together with other manual control switches, the switch 96 which has previously been described and an automatic or spring operated switch 118 which is placed in position in the drawer of a cash register, or in conjunction with the door of a safe or vault, or in any other suitable place where unauthorized tampering will cause the same to be closed and the circuit completed.

An alarm bell 119 or any other suitable electrically operated alarm apparatus may also be placed in shunt with the circuit so as to ring or operate when the switch 118 is closed by the unauthorized manipulation of the burglar.

The electric circuit for the motor 12 (Figure 17) which is like the motor 57, is used for returning the curtain to inoperative position, and comprises a manual control switch 120 and the reset switch 95. Substantially

the same circuit is used in connection with the motor 57, in this case the switch 56 taking the place of the switch 95.

The operation is as follows:

The operation of the device will be obvious from the foregoing description. Upon the closing of the spring switch 118 by the burglar or other unauthorized person, the circuit to the motor 23 is energized, and said motor is set in operation to cause an upward movement of the curtain 7. This movement is relatively slow and upon contact of the reinforcing strip 17 with the lever 80, weights similar to the weight 47 are released and the windows, doors and other openings are closed by curtains similar to the curtains 37. This closing of the windows and doors is rapidly effected since the weights like the weight 47 are preferably made heavy enough to cause a fast upward movement of the curtain and upon the doors and windows thus being closed, the burglar will naturally attempt to escape through the vestibule since the curtain 7 has not yet entirely closed and this offers an apparent avenue of escape. Said curtain 7 however in the meantime has travelled sufficiently high to prevent the burglar escaping therewith and ordinarily upon the burglar's reaching the vestibule the travel of the curtain 7 will have been sufficient to cause the reinforcing strip 17 to trip the lever 79 thereby releasing the weight 47 and causing a rapid upward movement of the curtain 37. In attaining this result the speed of the curtain 7 and the position of the lever 79 are varied in accordance with the size of the room or other enclosure. Thus, in a large majority of cases the burglar is very likely to be trapped in the vestibule during his efforts at escape. The control of the motors for returning the curtains to inoperative position is of course manually effected through switches similar to the switch 120 which are all preferably positioned in a locked and concealed compartment. Both in the upward and downward movement of the curtain the automatic resetting operations of the switches and clutches are effected in the manner previously described.

It will be apparent from the foregoing description that this invention affords an installation which may be concealed in such a manner that the presence thereof will not be noted by the casual observer and the installation itself serves as an effective method of trapping burglars and unauthorized persons in a confined compartment where there is little likelihood of their doing injury to other occupants of the enclosure which they have entered in an unauthorized manner.

The installation may also be set in op-

eration by lawful occupants of the building or the like in case of fire to isolate certain rooms of the building or to close the same against draughts which enhance the spread 5 of the fire.

It is desired, the entire installation may be disconnected for purposes of repair or inspection by opening the manual control switch 117.

10 I am aware that numerous details of construction may be varied through a wide range without departing from the principles of this invention, and I therefore do not purpose limiting the patent granted hereon, 15 otherwise than necessitated by the prior art.

I claim as my invention:

1. The combination with an enclosure having a vestibule, concealed protective shields for closing both ends of said vestibule, power operated means for elevating the outer shield, and means actuated after a predetermined elevation of the outer shield for elevating the inner shield for the purpose set forth.

25 2. The combination with an enclosure having openings therein, of a vestibule leading to one of said openings, protective shields for closing said openings including a protective shield at each end of said vestibule, power operated means for elevating said shields, and means for delaying the elevation of the inner shield of said vestibule

after the outer one has been partially elevated.

3. The combination with an enclosure 35 having a vestibule, a concealed protective shield at each end of said vestibule, rotatable power actuated means for raising and lowering said shields including automatically operated clutches and means operated 40 through the raising and lowering of said shields for controlling said clutches.

4. In a device of the class described, a flexible shield, a roller for securing the lower end thereof, a motor for elevating said shield, a motor for rotating said roller for lowering said shield, and means operable 45 during the lowering movements of said shield for controlling said motors and the operative connection of one of said motors.

5. In a device of the class described, a flexible shield mechanism for raising and lowering the same comprising a pair of motors, one of said motors having a clutch and means operated during the movements 50 of said shield for controlling said motors and said clutch.

In testimony whereof I have hereunto subscribed my name in the presence of two subscribing witnesses.

HARRY JACOB WERTHEIMER.
